2 Claims. (Cl. 158—4)

This invention relates to installations for generating streams of hot gas.

It is an object of the invention to provide a hot-gas generating installation which will supply a flow of hot gas at a relatively high rate, with the temperature thereof undergoing considerable periodic variations. It is a further object of the invention to provide such an installation with which the flow of gas supplied will be subject also to periodic variations in pressure and specific mass.

It is a further object of the invention to provide an installation which will supply a substantially continuous flow of gas comprising alternating sections or bursts of different temperatures.

According to the invention there is provided a hot gas generating installation comprising at least two (and preferably three or more) tubular burners arranged in succession, a first of said burners being of the acoustic resonance type, adapted to effect periodic combustion of fuel and combustion-supporting medium supplied thereto under pressure, so as to produce a stream of hot gas varying periodically at a frequency determined by the dimensions of said first burner and the pressures at which fuel and combustion-supporting medium are supplied, and a second of said burners being adapted to receive exhaust gas supplied thereto by said first burner, to effect combustion in said second burner.

Advantageously the following burner or burners is or are designed and shaped so as not to disturb, by their own operation, the frequency set up by the first burner.

The relative disposition and the arrangement of the successive burners are advantageously such that the hot gases discharged by one burner in the direction of the following burner effect at least the partial supply of the latter with combustion-supporting medium by an induction or pump effect, and the ignition of the following burner by pilot flame effect, that is to say, the exhaust gases supplied to the said following burner by the said one burner are at such a temperature that fuel is spontaneously ignited in the said following burner.

In a preferred embodiment of the invention, the burners extend, over a considerable part of their length, inside gas-tight chambers filled with compressed air or other supporter of combustion under pressure, serving to feed the burners.

The description which follows with reference to the accompanying drawing is given by way of non-limitative example only but will make clearly understood how the invention may be carried into effect, the details appearing both from the text and from the drawing forming part of the said invention.

The single figure of the drawing is a diagrammatic view in longitudinal section of one form of installation constructed in accordance with the invention.

Referring to the drawing, the installation comprises a series of three tubular burners 1, 2 and 3 arranged one after the other on the same axis X-Y and extending, over the major parts of their lengths, in gas-tight chambers 4 and 5 supplied with compressed air or other supporter of combustion under pressure, by way of conduits 6 and 7.

2

The leading burner 1, which includes a combustion chamber 8, is closed at its forward or upstream end and is connected in the downstream direction by a short convergent portion 9 to a tuyere 10 which opens into the chamber 4. The combustion chamber 8 is provided with injectors 11 which are located close to its forward end, adjacent a sparking plug 12, and are supplied with fuel through a pipe 13. Pipe lines 14 deliver compressed air into the combustion chamber 8 through one or more peripheral jets. Advantageously there are four jets arranged in opposite pairs, so as to produce good distribution of the supporter of combustion and strong turbulence in the region of the injectors 11.

This leading burner 1 is of the so-called acoustic resonance type, that is to say, combustion of fuel takes place therein in a spontaneously periodic manner, the frequency being a function of the geometrical dimensions of the burner and, in particular, a function of the total length of the burner and of the ratio of the volumes of the combustion chamber 8 and the ejection tuyere 10, and also a function of the pressures at which the fuel and the supporter of combustion are supplied. In fact:

For a given ratio of the volume of the combustion chamber to the volume of the tuyere, the shorter the burner the higher the frequency;

For a given total length, the frequency is reduced as the volume of the chamber is increased in relation to that of the tuyere;

Finally, for any given set of geometrical dimensions, the frequency increases when the pressures at which the supporter of combustion and the fuel are supplied are raised.

Of course, there are limits to the possible frequency variations, these limits being imposed by the stability of the self-igniting combustion and being a function of the nature of the fuel employed and of its ignition or firing time. Beyond these limits, resonant operation is unstable, or even impossible, in which case continuous combustion of low thermal efficiency takes place in the burner.

In practice, depending on the value of the geometrical parameters and of the supply pressures, the frequency of combustion of such a burner may vary from a few cycles per second to 600 cycles per second and even more where a fuel having a small ignition time is used. Thus the frequency of combustion can be adjusted within very wide limits, according to requirements.

The intermediate burner 2, located downstream of the previously mentioned burner 1, comprises basically a convergent portion 15 of evolute form leading into a divergent conical portion 16 terminating in an evolute widened portion 17 which connects the divergent conical portion 16 with a combustion chamber 18, the chamber 18 being generally cylindrical and extended by a short tuyere 19. Advantageously the latter is terminated by a short convergent portion 20. In the zone where the divergent portion 17 opens into the combustion chamber there is located a fuel feeding system consisting of one or more injectors 21.

The dimension of the intermediate burner 2 will be chosen in dependence upon those of the leading burner 1 and also upon the flow characteristics desired for the nominal supply pressure of the supporter of combustion (that is to say, the pressure prevailing in the chamber 4).

However, in designing the burner 2, it is of advantage to bear in mind the following considerations so that a departure may be made, as far as is possible, from the normal dimensional characteristics of pulsatory combustion chambers, in order that the working rhythm imposed by the leading burner 1 shall not be disturbed:

The total length of the burner 2 will generally be less

than five times the diameter of its combustion chamber 18;

The length of the divergent feed portion 15-16-17 will be of the same order of magnitude as the sum of the lengths of the combustion chamber 18, the ejection tuyere 19 and the convergent portion 20;

The length of the combustion chamber 18 will be of the same order of magnitude as the length of the tuyere 19, while the diameter of the latter will be more than 70% of the diameter of the combustion chamber;

The angle of the conical part of the divergent portion 16, relatively to the central axis, will be of the order of 8° and its smallest cross-section will have an area greater than that of the cross-section of the tuyere 10 of the leading burner 1.

The final or tail burner 3 is of similar form to the burner 2. In this case we again find an evolute convergent portion 22, a conical divergent portion 23, a connecting divergent portion 24 and a cylindrical combustion chamber 25 connected by a convergent portion 26 to a terminal tuyere 27 which may be either of circular or bi-dimensional cross-section, that is to say, having a four sided cross-section such as a square or rectangle. In the latter case, the convergent portion 26 will provide a gradual transition between the larger circular cross-section of the combustion chamber 25 and the slightly smaller bi-dimensional cross-section of the tuyere 27. Fuel injectors 28 are located in the region of the connecting portion 24, that is to say, between the divergent feed portion 23 and the combustion chamber 25. Oxygen feed nozzles 29 are advantageously provided upstream of the fuel injectors 28 in the conical divergent portion 23.

For determining the dimensions of the tail burner 3, it is of advantage to take into account the following considerations:

The sum of the lengths of the divergent portions 22, 23 and 24, the combustion chamber 25 and the connecting convergent portion 26 should be smaller than the length of tuyere 27;

The length of the combustion chamber 25 should be less than twice its diameter;

The conical divergent portion 23 has an angle of the order of 8° relatively to the central axis and its smallest cross-section has an area larger than the area of the cross-section of the ejection tuyere 19 of the intermediate burner 2.

Each chamber 4 or 5 may be formed by a cylindrical element terminating at its ends in two hemispherical portions having orifices limited by flanges. To the latter there are fixed mating-flanges carried by the burners and forming the fixing means for the latter. The orifices are designed so as to permit easy mounting and removal of the burners.

The arrangement which has just been described operates in the following manner:

As has already been mentioned, the leading burner 1 (hereinafter called the "acoustic burner") operates at a given frequency which can be regulated.

The kinetic energy of the gas periodically ejected by the tuyere 10 of the burner 1 ensures that the intermediate burner 2 (hereinafter called the "non-resonant burner") periodically receives supporter of combustion from the chamber 4, by a pump action in accordance with the well-known phenomenon of pulsed dilution. When supporter of combustion fed into the burner 2 in this way flows into the region of the fuel injectors 21 which are arranged at the inlet of the combustion chamber 18 of the non-resonant burner 2, it forms a carburetted mixture which is periodically ignited under the action of the hot gases issuing from the acoustic burner 1. In this way combustion takes place in the non-resonant burner 2 at the frequency determined by the periodic combustion in the acoustic burner 1.

The advantage of arranging the two types of burners

in succession arises from the fact that the acoustic resonance burner 1 is necessarily of small dimensions in order that the frequency of combustion should, as is desirable, exceed some hundred cycles per second. The small volume imposed on this acoustic burner 1 has the result of limiting rather closely the mass and rate of flow of gas which it is capable of producing. On the other hand, since the performance of the non-resonant burner 2 is not limited by the requirements of self-feeding and self-ignition, it can considerably increase the mass and rate of flow of the gases subjected to the thermodynamic process. In brief, it can be said that the acoustic burner 1 determines the frequency of the periodic combustion while the non-resonant burner 2 determines the rate of flow or delivery. Thus it is possible for an installation constructed in accordance with the invention to include only two burners if desired.

As regards the installation shown in the drawings, the tail burner 3 (hereinafter called the "post-combustion burner") is supplied, in its turn, by supporter of combustion from the chamber 5 by the action of the kinetic energy of the gases which issue periodically from the burner 2 and exert an induction effect. This supporter of combustion is enriched with oxygen at 29 as it passes through the intake nozzle 23 of the post-combustion burner.

The periodic combustion of the fuel, in the presence of air enriched with oxygen and heated by admixture with the hot gases ejected by the non-resonant burner 2, as well as by heat transmitted by the walls of the burners 2 and 3 by convection and radiation, makes it possible to obtain, at the frequency determined by the acoustic burner 1, the periodic production of masses of gas at high temperature which are supplied in the form of hot bursts in the flow emerging from the ejection tuyere 27.

The function of the gas-tight chambers 4 and 5 is to permit the non-resonant burner 2 and the post-combustion burner 3 to be supplied with supporter of combustion at elevated pressure. In the case of either chamber, the supporter of combustion may be ordinary compressed air or compressed air enriched with oxygen.

Moreover, these chambers considerably reduce the thermal losses of the installation, particularly when they are provided with thermal insulation since the calories of heat transmitted by the walls of one burner are almost wholly recovered by the supporter of combustion which is used at the following combustion stage.

Finally, these chambers have a silencing function, which is particularly important since the noise level of periodic burners is always high by reason of the strong pressure vibrations which they set up.

It is to be observed that with such an installation a large number of adjustable parameters is available. In addition to the geometrical dimensions on which the frequency depends, it is possible to regulate the pressure—and consequently the rate of flow—of the fuel feeding the three burners. Likewise the three systems for supplying supporter of combustion to the respective burners are individually adjustable in pressure. In this respect, it is desirable that the pressure at which the leading burner 1 is supplied with supporter of combustion should be higher than the pressure of the supporter of combustion contained in the chamber 4 and supplying the intermediate burner 2, this latter pressure in turn being higher than the pressure of the supporter of combustion contained in the chamber 5 and intended for the tail burner 3.

It is also possible to effect regulation by varying the operating temperatures. Thus, the supporter of combustion can be pre-heated before admission into the chambers 4 and 5 to selected temperatures which, however, must of course be compatible with the behaviour of the materials used in the construction of the installation.

Finally, the rate of enrichment of the supporter of combustion with oxygen for the purposes of post-combustion in the chamber 3 can be regulated by modifying its

supply pressure, this having a direct influence on the temperature reached by the hot sections or bursts of the flow.

In short, it will be seen that it is easily possible in this way to fix the duration of the alternately very hot and less hot flow bursts which the generator will deliver through its outlet tuyere 27.

The gas generator of the present invention is susceptible of many applications, the most interesting of which will, it appears, lie in the fields of testing refractory materials, of experimental studies of non-uniform flow and of the direct conversion of heat energy into electrical energy by so-called magneto-gas-dynamics.

For this last application, one of the burners will generally be equipped with a complementary feed device by means of which a solution of a readily ionisable substance, such as potassium, is introduced into the flow.

It is obvious that modifications may be made in the form of installation which has just been described, in particular by substituting equivalent technical means, without thereby departing from the scope of the present invention as defined by the appended claims.

What we claim is:

1. A hot gas generating installation comprising a first, a second and a third intermittent-combustion duct means axially arranged in series, fuel injector means in each of said duct means, each of said duct means having a discharge nozzle, inlet passage means in said second duct means positioned adjacent the discharge nozzle of said first duct means, inlet passage means in said third duct means positioned adjacent the discharge nozzle of said second duct means, said inlet passage means of said second and third duct mean arranged to collect the gases discharged from the discharge nozzles of said first duct

means and said second duct means respectively and co-operating therewith to produce an injector effect inducing ambient fluid into said second and third duct means, a gas-tight casing surrounding and enclosing a substantial part of said second and third duct means including the discharge nozzle of said second duct and the inlet passage means of said third duct means, oxygen supply means in said third duct means, and means for supplying combustion-supporting gas under pressure into said gas-tight casing.

2. Installation as claimed in claim 1, comprising further a gas-tight casing surrounding and enclosing a substantial part of the first and second duct means including the discharge nozzle of said first duct means and the inlet passage means of said second duct means, and means for supplying combustion-supporting gas under pressure into said last mentioned gas-tight casing.
